Primary Examiner — Cynthia M. Chin(74) *Attorney, Agent, or Firm* — AP3 Law Firm PLLC(57) **CLAIM**

The ornamental design for a skate with wireless hand control as shown and described.

DESCRIPTION

FIG. 1 is a front view of a skate according to our new design, shown separately for the clarity of illustration;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a rear left perspective view thereof;

FIG. 8 is a front view of a wireless hand control for speed and power settings of the skate, shown separately for the clarity of illustration;

FIG. 9 is a right side view of the wireless hand control;

FIG. 10 is rear view thereof;

FIG. 11 is left side view thereof;

FIG. 12 is a top view thereof;

FIG. 13 is a bottom view thereof;

FIG. 14 is a front perspective view thereof; and,

FIG. 15 is a rear perspective view thereof.

The broken lines are for the purpose of illustrating portions of the article that form no part of the claimed design.

1 Claim, 11 Drawing Sheets(56)
